CLAIM

The ornamental design for a wire plate for notification appliance, as shown and described.

DESCRIPTION

FIG. 1 is a perspective view of a wire plate for notification appliance;

FIG. 2 is a front view of the wire plate for notification appliance of FIG. 1;

FIG. 3 is a right side view of the wire plate for notification appliance of FIG. 1, the left side view being a mirror image of the right side view shown;

FIG. 4 is a first end view of the wire plate for notification appliance of FIG. 1;

FIG. 5 is a second end view of the wire plate for notification appliance of FIG. 1; and,

FIG. 6 is a back view of the wire plate for notification appliance of FIG. 1.

The broken lines illustrate portions of the wire plate for notification appliance that form no part of the claimed design.

1 Claim, 5 Drawing Sheets
